Attorney

UNITED STATES PATENT OFFICE.

HARRY L. GRANT, OF TAMAQUA, PENNSYLVANIA, ASSIGNOR TO ATLAS POWDER COMPANY, OF WILMINGTON, DELAWARE, A CORPORATION OF DELAWARE.

PROTECTING DEVICE FOR ELECTRIC DETONATORS.

Application filed November 20, 1925. Serial No. 70,369.

This invention relates to a protecting device for electric detonators of the character of that shown in my copending application, Serial No. 748,214, filed on November 6, 5 1924.

Like the device of the application referred to, the protecting device of the present invention is intended to be applied to the lead-in wires of electric detonators and 10 to serve, while in position, to establish a short circuit between the two lead-in wires, so that any stray currents imposed upon the lead-in wires, outwardly of the point of application of said device, may not find 15 their way to the detonator and prematurely explode the same.

I am aware of the fact that it has been proposed to short circuit the main firing cable leading from the blasting machine. 20 However, that method is of utility only at the time of use. An important object of the present invention is to provide a structure which will be operative with respect to the individual detonators, at all times between 25 the time of manufacture of the detonator and until the same is actually exploded on the job, the structure being of particular utility during the time that the detonator is being transported and while it is being 30 handled about the work preliminary to the actual connection of its lead wires to the main firing cable.

The present application is directed to the protection of a specific form of short circuiting shunt and method of applying the same to the lead-in wires of the individual blasting caps, preferably with its inner end abutting and resting firmly against the terminal end of the usual insulation of the 40 detonators. In the provision of a structure of this character, which is used only once and then thrown away, it is of importance that it be of a simple and inexpensive nature and one adapted to be applied rapidly 45 by automatic machinery. With this end in view, I have devised the shunt shown in the accompanying drawing wherein:

Fig. 1 is a side elevation of a detonator having a spiral shunt applied thereto,

50 Fig. 2 is a fragmentary side view of the same upon an enlarged scale,

Fig. 3 is a cross sectional view of the shunt of Fig. 2 before its deformation by pressure,

55 Fig. 4 is a view of the shunt of Fig. 1

after it has been compressed into intimate engagement with the detonator lead wires,

Fig. 5 is a side view of a modified form of shunt and

Fig. 6 is a cross sectional view of the 60 shunt of Fig. 5.

Like numerals designate corresponding parts in all of the figures of the drawing.

Referring to the drawing, 5 designates the conventional electric detonator and 6 and 7 65 designate the usual lead-in wires of said detonator.

In the ordinary use of the detonator the flow of current of sufficient strength past an igniting element 8, which connects the 70 inner ends of the wires 6 and 7, explodes the detonator. The lead-in wires are insulated, as indicated at 9 and 10, for some distance from the detonator and the ends of the lead-in wires are left bare beyond the point where 75 the insulation terminates, to adapt them for ready application to the firing cable, leading from a blasting machine.

The shunt of the present invention is 80 formed from sections of spiral tubing which are cut to suitable lengths, the lead wires are threaded therethrough, and then the spiral tubing is deformed by pressure to 85 press its convolutions into intimate contact with the lead wires at a plurality of points in the length of the latter.

In the form of the invention illustrated in Figs. 1 to 4, 11 designates a spiral winding of wire of any suitable conductive material which may be a section of spiral tubing, of circular form in cross section, preferably so positioned upon the lead wires 6 and 7 that its inner end abuts the insulation upon said lead wires. After the lead wires have 90 been threaded through the section of spiral tubing, said tubing is deformed or flattened by the application of pressure to the form 95 illustrated in Fig. 4, so that it tightly grips and engages the surfaces of said lead wires. The winding 11 may be of copper, aluminum or any other suitable metal.

In the form of the invention illustrated in Figs. 5 and 6, the principle is the same, in that a tubular spiral is applied to the lead 100 wires close enough to the insulation upon said lead wires to practically prevent the creation of a difference of potential between said wires, inwardly of the point of application of the device, under the influence of accidental or stray currents imposed upon 110

2
said wires, under any conditions. However, in this case, the spiral winding, indicated at 11^a, is, when finally compressed into engagement with the lead wires, of substantially 5 triangular form in transverse section.

When it is desired to remove the shunt from the lead wires, at the time of use of the detonator, said shunt may be stripped longitudinally from said wires. This act of stripping 10 the shunt from the wires cleans and brightens them and puts them into condition to make effective electrical union with the main firing cable of the blasting machine.

15 It is to be noted that each and every convolution of the shunt will be pressed into contact with the lead wires, so that there will be a plurality of engaging surfaces, each of which will aid in the cleansing and scraping 20 action as the shunt is stripped from the lead wires. It is not to be understood that the device is of utility only when actually touching the termination of the insulation. It will give a very appreciable measure of 25 protection even when spaced somewhat from the insulation because the influences which might bring about such difference in potential between the lead wires as to explode the detonator, are not those sought to be created 30 by an intelligent human agency but only those which might accidentally occur. Stray currents of such low E. M. F. as to escape ordinary notice constitute a marked

source of danger and are rendered absolutely 35 harmless by this invention.

It is to be understood that the invention is not limited to any particular formation for the finished or compressed shunt but that it includes any spirally wound tubular shunt, the material of which is compressed 40 into intimate and forcible contact with the surfaces of the lead wires after the lead wires have been threaded therethrough.

Having described my invention, what I 45 claim is:

1. A shunt of the character described comprising a spiral of conductive material which has been flattened by pressure after application to the wires to be joined.

2. The combination with a detonator and 50 its lead wires, portions of which lead wires are covered with insulating material and the remainder of which lead wires are bare, of a shunt comprising a tubular spiral, positioned upon the bare portion of said wires 55 and lying close enough to the terminal ends of the insulation to practically prevent the creation of a difference of potential between the lead wires inwardly of the point of application of the shunt, said spiral being deformed by pressure to cause its several convolutions to firmly engage the bared portions of the lead wires.

In testimony whereof he affixes his signature.

HARRY L. GRANT.
